CLAIM

The ornamental design for a vial cap lock, as shown and described.

DESCRIPTION

FIG. 1 is a perspective view of a first embodiment of a vial cap lock.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof;

FIG. 9 is a third perspective view thereof;

FIG. 10 is a perspective view of a second embodiment of a vial cap lock.

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a second perspective view thereof; and,

FIG. 18 is a third perspective view thereof.

The broken lines in the form of a vial depict environmental subject matter and form no part of the claim thereof. All the other broken lines shown in the drawings depict portions of the vial cap lock that form no part of the claimed design.
